**APPARATUS AND METHOD FOR MINING
GRANULAR ORE**

Harry B. Cannon, Sr., Harry B. Cannon, Jr., and Hugh N. Cannon, all of P.O. Box 2432, Lakeland, Fla. 33802
Filed Apr. 9, 1964, Ser. No. 359,552
12 Claims. (Cl. 299—18)

This application is a continuation-in-part of copending application Ser. No. 308,244, filed Sept. 11, 1963, and now abandoned.

This invention relates to an apparatus and method for the deep-well mining of granular ore, and it more particular relates to such an apparatus and method for the mining of granular phosphate ore.

In existing methods for deep-well mining of granular ore such as phosphates, the ore is diluted in situ by jetting water into the matrix in an attempt to wash it into the suction of a pump loosely inserted through a well casing. Such methods suck cavities in the ore matrix which develop into efficient filter chambers that accept water from the surrounding sands but prevent the ore from migrating to the well pipe. In such cavities the angle of ore repose reaches the vertical to cause small diameter vertical shaft-like withdrawal and minimum ore production per well.

An object of this invention is to provide a simple and efficient apparatus and method for deep-well mining of granular ore.

In accordance with this invention, a positive displacement pump is sealed to the lower end of a conduit well which is inserted down through the ground into the bed or matrix of granular ore. The lower end of the conduit is sealed within the ground to cause the positive displacement pump to concentrate on drawing the granular ore in its undiluted natural state into the conduit and force it to the surface of the ground. Broad subsidence of the matrix is therefore induced without caving. A foot extension on the conduit below the pump supports it upon a basal shelf under the matrix and above any layer of undesirable material upon it. Fluid may be added to the ore within the suction chamber of the pump to dilute it and therefore facilitate its movement to the surface.

In an advantageous form of this invention, a vertically reciprocating type of positive displacement pump is formed by a plunger inserted within the bottom of the conduit above a foot valve. A check valve in the plunger opens upon downward movement of the plunger to force any ore in the suction chamber above the foot valve up through the plunger into the conduit where it is pushed by successive strokes up to the surface. Upward strokes close the check valve and suck ore through the foot valve to the suction chamber. Water is pumped into the suction chamber through a hollow plunger rod to dilute the granular ore and facilitate its movement to the surface. The water is controlled to be introduced principally on the downward stroke. The upper end of the conduit can be insulated from subsidence of the ore strata and overburden by supporting it upon a barge floating upon a dammed pool of water, the surface of which is maintained at a substantially constant level.

In accordance with another aspect of this invention a turbine pump is inserted in a conduit well which is sealed in the ground and extends into the bed of granular ore. As natural ore is drawn through holes in the bottom of the conduit dilution water is applied to it in the conduit to facilitate its movement to the surface of the ground by the action of the turbine pump. The dilution water may be applied at a slower rate than the rate at which the matrix is sucked into the conduit to assure that matrix outside of the conduit is not diluted.

2

Novel features and advantages of the present invention will become apparent to one skilled in the art from a reading of the following description in conjunction with the accompanying drawings wherein similar reference characters refer to similar parts and in which:

FIGS. 1-2 are cross-sectional views in elevation of one embodiment of the invention showing different phases of operation;

FIGS. 3-4 are exploded cross-sectional views in elevation of a portion of the apparatus shown in FIG. 2 showing different phases of operation;

FIG. 5 is a cross-sectional view in elevation of an alternative form of the invention shown in FIGS. 1-4; and

FIG. 6 is a cross-sectional view in elevation of an alternative form of the invention shown in FIGS. 2-4.

In FIG. 1 is shown a barge 12 which is used for setting mining apparatus 10 into a matrix or bed of granular ore 14. Barge 12, which floats in water such as a dammed pool above the strata or overburden covering matrix 14, comprises a platform 15 mounted on a pair of parallel spaced pontoons 16. Drilling equipment 18, such as a conventional cable tool or rotary-type rig, is mounted on barge 12 in a slot between pontoons 16 and drills a hole from ground surface 20 to the base of the bed of matrix or granular ore 14. As the hole or deep well is dug, it is mudded to make its side walls temporarily self-supporting. The various components of mining apparatus 10 are then inserted into the hole from barge 12. Well pipe or conduit 26 of mining apparatus 10 is of the same diameter as the predrilled hole and is thus sealed in the hole. Since pipe or conduit 26 is of the same diameter as the hole, it can be lowered through hard rock layers below the surface through a minimum size hole inasmuch as it has no outside connections, protuberances or irregularities. Additionally, while well pipe 26 is being lowered to its operating position, it cleans caved solids from its path, thus obviating the necessity of an auxiliary casing.

Where no layer of limestone or cap rock covers the matrix, the deep well is drilled by well pipe or conduit 26 itself without any predrilling by using a conventional simultaneous-jet-jar drive with a cable tool rig or by pumping well pipe 26 into the ground through its own pumping action with the use of a cable tool rig.

After mining apparatus 10 is set, barge 12 moves away and mining barge 22, constructed similarly to barge 12, then floats to the deep well. Pump drive 24 for the particular type of pump, such as a turbine or rotary pump 27 as shown in FIGS. 6 and 7 or a vertically reciprocating jack pump 25 as shown in FIGS. 3 and 4, is mounted on barge 22 for removing ore from matrix 14 to a recovery receptacle in barge 22. In FIG. 2 pump drive 24 is shown as a reciprocating mechanism for operating jack pump 25, later described in detail. Since the lower end of mining apparatus 10 is sealed within the ore bed, only the ore migrates to it and since the ore or matrix supporting the strata is removed over a large area the strata above it gradually lowers as broad subsidence is induced without any local caving as shown in FIG. 2. The matrix is removed over a large area because this high density pumping without caving stimulates extended subterranean flow at relatively flat slopes and produces a maximum tonnage of mined ore per well. Since barge 22 floats, it maintains pump drive 24 at substantially a constant elevation throughout the mining of ore 14 and thus insulates the upper end of conduit 26 from the subsidence of the matrix and overburden. After the well has been completely mined, mining barge 22 moves off and setting barge 12 returns to recover the pumping equipment.

In FIGS. 3 and 4 is shown vertically reciprocating jack pump 25 which operates in conduit 26. The base of well pipe or conduit 26 is perforated, providing an inlet 28 for the ore. Since the perforations in pipe 26 are below the limestone cap and pipe 26 extends above the ground surface, the strata above ore 14 is not mined. Foot extension 29 supports conduit 26 below pump 25 upon basal shelf 31 under matrix 14. Apertured partition 30 in the base of well pipe 26 separates intake chamber 32 exposed to ore 14 from suction chamber 34. Ball 36 of foot valve 41 floats in suction chamber 34 and upon the downward stroke of plunger 38 is seated in aperture 35 to close foot valve 41 and thus seal chambers 32 and 34 from each other. Plunger or pump rod 38 reciprocates in suction chamber 34 and carries a perforated flange or piston head 40 which separates suction chamber 34 from outlet chamber 42. Floating disc or valve head 44 of check valve 45 is seated upon perforated head 40 when plunger 38 is in its upward stroke to seal chambers 34 and 42 from each other. Outlet 46 in outlet chamber 42 opens into a recovery receptacle (not shown) above the ground surface. A hose or tube 48 leads from a source of water (not shown) under pressure and is connected to plunger 38, which is hollow, to provide a fluid passage for feeding water into suction chamber 34. The fluid is intermittently supplied to suction chamber 34 to dilute the ore in the suction chamber. The cyclical control of fluid introduction is accomplished by a sleeve valve (not shown) which is attached to plunger 38 or by solenoid valve 50, later described in detail, to close the passage on the up stroke of the plunger and to open it on the down stroke. The cyclical water introduction increases the efficiency of jack pump 25 which applies a positive suction pressure approaching the maximum of 30 feet.

When plunger 38 is moved in its upward or lift stroke, suction is created in suction chamber 34 to unseat foot valve ball 36 and to suck ore 14 from intake chamber 32 into suction chamber 34. At the end of the upward stroke, actuating projection 54 hits switch 52 to open solenoid valve 50. When plunger 38 is moved in its downward stroke, pressure is increased in suction chamber 34 and decreased in outlet chamber 42 to unseat floating check valve head 44 and to seat foot valve ball 36. Since suction chamber 34 is sealed by foot valve 41, the water entering the suction chamber cannot escape to the bed of matrix 14 but dilutes the ore in suction chamber 34 to create a slurry which is washed through piston head 40 and around check valve head 44 in outlet chamber 42. At the end of the downward stroke, actuating projection 55 hits switch 52 to close valve 50. When plunger 38 is again moved upward, suction is created in chamber 34 to unseat foot valve ball 36 sucking more high density natural ore into chamber 34 and simultaneously, as pressure in chamber 42 is increased, pressure and the weight of the slurry or diluted ore seats valve head 44 to close communication between suction valve 34 and outlet chamber 42. As the plunger continues to move upward, the ore is forced from outlet 46 through successive strokes into the recovery receptacle. By this continuous process, the ore is sucked into conduit 26 in its natural undiluted state, is diluted in chamber 34 and is forced intermittently or pulsatingly to the surface. Since conduit 26 is sealed in, only matrix 14 migrates to conduit 26 and the overlying strata gradually lowers or subsides over a broad area without producing any local cavities.

In FIG. 5 is shown an alternative construction for well pipe or conduit 26. In this form the conduit comprises a pair of inner and outer casings 70 and 72. Sealing material 74 fills the annular space between the casings to provide a sealed-in deep well. This form of construction is useful to protect inner pump casing 70 from being damaged by caved or subsiding solids in the predrilled hole when casing 70 is inserted for operation.

In the embodiment shown in FIG. 6 the ore is recovered through conduit 26 by turbine pump 76. Conduit 26 is sealed in the well at its upper end and rests on basal shelf 31 by foot support 29. Flange 92 mounts conduit 26 to platform 94 above the ground. Turbine pump 76 includes a bowl assembly 78 consisting of an outer stator 80 and a plurality of rotors or vanes 82 having bearings 92. Rotors 82 are driven by a hollow shaft 84 from a drive mechanism (not shown) above the ground. Shaft 84 is enclosed in and protected by concentric tube 86 which together with casing 88 forms a passage 89 for the ore to discharge it into the recovery receptacle through outlet 90. Water is fed into conduit 26 through tubular extension 96 to dilute the natural ore in the bottom of conduit 26 and facilitate its movement through passage 89, while bypass line 98 joins extension 96 and the hollow interior of drive shaft 84 to lubricate bearings 92 through ports 100 at each bearing.

When the drive shaft 84 is rotated, turbine pump 76 sucks natural ore into conduit 26 through openings 28 at the bottom of the conduit. The entire bottom portion of conduit 26 thus forms a suction chamber. The ore in its natural state is diluted by water in this suction chamber and the diluted ore is sucked into bowl assembly 78 through passage 89 and discharged from outlet 90 into the recovery receptacle. The dilution water is fed into conduit 26 at a slower rate than the slurry or diluted ore is pumped from conduit 26 to insure that water will not escape through openings 28 and dilute the ore outside of conduit 26. Thus since the dilution is confined to conduit 26 the overlying strata gradually lowers or subsides over a broad area without producing any local cavities. Because tubular pump 76 is continuously sucking the ore into conduit 26 and through bowl assembly 78, the slurry 35 is non-intermittently or continuously discharged from outlet 90 to substantially reduce the amount of time required to mine the granular ore.

What is claimed is:

1. An apparatus for mining granular ore through a well 40 in the ground comprising a conduit extending from above said ground into the bed of granular ore, the bottom of said conduit being sealed in said well, a positive displacement pump being sealed to the bottom of said conduit which sucks ore into said conduit and pumps it above said ground whereby said undiluted ore bed is caused to continuously laterally flow and broadly subside toward said pump without cavitation, said positive displacement pump comprising a plunger rod extending from above said ground to the lower end of said conduit, an inlet opening in the bottom of said conduit, a foot valve in said conduit above said inlet opening to form a suction chamber below said plunger rod, a check valve in said plunger for causing said ore to pass upwardly through said plunger and said conduit, said plunger rod being hollow, a source 45 of water connected to the upper end of said plunger rod, a reciprocating means connected to the upper end of said plunger rod for causing said plunger rod to move up and down whereby ore is successively sucked into said suction chamber and forced upwardly by said plunger rod through said conduit, an outlet at the top of said conduit above said ground level, water control means connected to said hollow plunger rod for introducing water into said suction chamber principally upon downward movement of said plunger rod, and the upper end of said conduit and said means for reciprocating said plunger being supported upon a floating platform whereby they are maintained at a substantially constant elevation as said ground surface subsides.

2. An apparatus for mining granular ore through a well 70 in the ground comprising a conduit extending from above said ground into the bed of granular ore, the bottom of said conduit being sealed in said well, a positive displacement pump being sealed to the bottom of said conduit which sucks ore into said conduit and pumps it above said ground whereby said undiluted ore bed is

caused to continuously laterally flow and broadly subside toward said pump without cavitation, said positive displacement pump comprising a plunger rod extending from above said ground to the lower end of said conduit, an inlet opening in the bottom of said conduit, a foot valve in said conduit above said inlet opening to form a suction chamber below said plunger rod, a check valve in said plunger for causing said ore to pass upwardly through said plunger and said conduit, said plunger rod being hollow, a source of water connected to the upper end of said plunger rod, a reciprocating means connected to the upper end of said plunger rod for causing said plunger rod to move up and down whereby ore is successively sucked into said suction chamber and forced upwardly by said plunger rod through said conduit, an outlet at the top of said conduit above said ground level, water control means connected to said hollow plunger rod for introducing water into said suction chamber principally upon downward movement of said plunger rod, said water control means comprising a solenoid valve connected to said source of water, a pair of spaced actuating projections on said plunger rod and switch means on said conduit connected to said solenoid valve, one of said actuating projections being disposed to contact said switch means at the end of the upward stroke of said plunger rod to open said solenoid valve, and the other of said actuating projections being disposed to contact said switch means at the end of the downward stroke of said plunger to close said solenoid valve whereby water is introduced into said suction chamber only upon said 30 downward stroke of said plunger rod.

3. An apparatus for mining granular ore through a well in the ground comprising a conduit extending from above said ground into the bed of granular ore, said conduit being sealed in said well, an inlet opening in the bottom of said conduit for permitting said granular ore to enter said conduit, water feeding means for diluting said ore in said conduit and allowing the ore in said bed outside of said conduit to remain undiluted, a pump in said conduit above said inlet opening for sucking undiluted ore into said conduit and pumping ore above said ground whereby said undiluted ore is caused to continuously laterally flow and broadly subside toward said pump without cavitation, said pump being a turbine pump, said turbine pump having a drive shaft, a hollow casing communicating with said turbine pump and being mounted concentrically around said drive shaft to provide a discharge passage for said ore, an outlet in the upper portion of said conduit communicating with said passage for discharging said ore therefrom, an inner casing being mounted about said drive shaft to shield said drive shaft from the ore in said passage, and said inner casing being disposed within and spaced from said hollow casing whereby the space between said casings comprises said ore discharge passage.

4. An apparatus for mining granular ore through a well in the ground comprising a conduit extending from above said ground into the bed of granular ore, said conduit being sealed in said well, an inlet opening in the bottom of said conduit for permitting said granular ore to enter said conduit, water feeding means for diluting said ore in said conduit and allowing the ore in said bed outside of said conduit to remain undiluted, a pump in said conduit above said inlet opening for sucking undiluted ore into said conduit and pumping ore above said ground whereby said undiluted ore is caused to continuously laterally flow and broadly subside toward said pump without cavitation, said pump being a turbine pump, said

turbine pump having a drive shaft, a hollow casing communicating with said turbine pump and being mounted concentrically around said drive shaft to provide a discharge passage for said ore, an outlet in the upper portion of said conduit communicating with said passage for discharging said ore therefrom, said drive shaft being hollow, bearing means being disposed around said shaft and communicating with its hollow interior, and said water feeding means leading to said hollow interior to provide a continuous passage for lubricating said bearing means.

5. A method of mining granular ore comprising the steps of drilling a hole from the ground surface into a bed of said granular ore through a layer of water impervious strata, inserting a conduit in said hole, sealing a portion of said conduit in said layer of strata, inducing the ore to broadly laterally subside without cavitation by applying suction at the bottom of said conduit to the undiluted ore to cause it to flow into the bottom of said conduit and by preventing dilution of the ore outside the conduit, and pumping the ore upwardly through said conduit.

6. A method as set forth in claim 5 wherein water is mixed with said ore within said conduit to dilute the ore in said conduit and facilitate its movement to the surface.

7. A method as set forth in claim 5 wherein said conduit is sealed within said hole by mudding it before inserting said conduit to cause it to stand up temporarily and thus seal about said conduit after it is inserted.

8. A method as set forth in claim 5 wherein said steps of drilling said hole and inserting and sealing said conduit within it are done simultaneously by pumping said conduit into the ground.

9. A method as set forth in claim 5 wherein the upper end of said conduit is supported upon a floating platform, said floating platform being floated upon the surface of a pool of water, and the surface of said platform being maintained at a substantially constant elevation to accordingly maintain said upper end of said conduit at a substantially constant elevation as said ground subsides as said ore is pumped from under it.

10. A method as set forth in claim 5 wherein a positive displacement pump is inserted within said conduit and said step of pumping is intermittent by means of said positive displacement pump.

11. A method as set forth in claim 5 wherein a turbine pump is inserted within said conduit, and said step of pumping is continuous and non-intermittent by means of said turbine pump.

12. A method as set forth in claim 11 wherein water is fed into said conduit at a slower rate than said ore is pumped from said conduit whereby the ore outside of said conduit is not diluted by said water.
